HARRY L. VAUGHAN, OF CHICAGO, ILLINOIS.

THROAT FOR BOTTLING-MACHINES.

1,104,023.

Specification of Letters Patent.

Patented July 21, 1914.

Application filed January 15, 1910. Serial No. 538,184.

To all whom it may concern:

Be it known that I, HARRY L. VAUGHAN, residing in Chicago, in the county of Cook and State of Illinois, have invented new and 5 useful Improvements in Throats for Bottling-Machines, of which the following is a description, reference being had to the accompanying drawings, which are a part of this specification.

10 This invention relates to a throat for use with bottling machines to clamp the crown cap to the mouth of the bottle and has for its object to simplify the construction thereof by forming the tapering composition 15 metal throat piece of an integral ring instead of in segments, thereby reducing the cost of manufacture and enabling the throat piece to be readily renewed when worn without the necessity for returning the throat to 20 the manufacturer.

Another object of the invention is to provide spring actuated crown retaining dogs of 25 novel construction which will be permanently held in place against accidental removal, but which will be freely accessible for repair.

With the above and other objects in view the invention consists in the throat for bottling machines herein described, its parts and combinations of parts as claimed and 30 all equivalents thereof.

Referring to the accompanying drawing in which like characters of reference indicate similar parts in the different views: Figure 1 is a sectional view of a throat embodying one form of the invention designed 35 for use on automatic bottling machines where the crown caps are automatically fed and supported in position; Fig. 2 is a similar view of a throat embodying another form 40 of this invention for use with bottling machines in which the crown caps are fed by hand and are retained in position by spring dogs within the throat, the section being taken on the plane of line 2—2 of Fig. 4; Fig. 3 is a similar view thereof on the plane 45 of line 3—3 of Fig. 4; Fig. 4 is a bottom plan view thereof with the sleeve sectioned to remove the retaining flange; Fig. 5 is a perspective view of the composition metal 50 throat piece of the form of throat shown in Figs. 2, 3, 4 and 6; Fig. 6 is a sectional view taken on the plane of line 6—6 of Fig. 4; Fig. 7 is a detail view of an implement designed 55 for use in removing the throat piece from the casing; Fig. 8 is a transverse sectional view of a throat, showing a further

modification of the invention; Fig. 9 is a view thereof similar to Fig. 4, with a part sectioned to show the manner of seating the dog springs; and, Fig. 10 is a perspective view of one of the crown cap retaining dogs.

In these drawings 15 indicates a tubular casing with an inwardly extending annular flange 16 at its upper end forming an abutment for the thicker upper end of a throat piece 17 which tightly fits within the casing 15 and has a tapering bore for crowding to withstand the action of the crown cap such as 18 in Fig. 3, to secure the cap to the mouth of a bottle when the bottle neck with the crown is forced into the tapering bore or throat-way of the throat piece. The throat piece 17 consists of an integral ring of composition metal which is sufficiently hard to withstand the action of the crown cap teeth without becoming gouged thereby. The throat piece 17 is held within the casing 15 by means of a flanged sleeve 19 which may be threaded on the casing 15, as shown in the forms of the invention illustrated in Figs. 1, 8 and 9, or which may have a tight working fit on the outside of the casing, as shown in the form of the invention, illustrated in Figs. 2, 3, 4 and 6. The flange 16 of the casing may be provided 55 with a pair of openings 20 through which a pair of pins 21 of the repair implement shown in Fig. 7 may be inserted to engage the larger upper end of the throat piece 17 for driving said throat piece out of the casing after the sleeve 19 has been removed, said repair implement being struck on its upper cross piece 22 by means of a hammer for this purpose. The throat piece 17 is keyed in the casing 15, as shown in Fig. 3, 95 by means of key pins 23 fitting in openings which pass through the flange 16 and are formed partly in the inner wall of the casing 15 and partly in the outer wall of the throat piece 17 and another opening 24 in 10 the upper end of the casing forms a seat for a projection on the machine as usual.

With those forms of the invention shown in Figs. 2 to 9 inclusive, the casing 15 and the throat 17 are made somewhat longer 10 than the corresponding parts in the form of the invention shown in Fig. 1, to provide sufficient space beneath the lower end of the tapering throat way for crown cap retaining dogs 25 which are relied upon to support the crown cap, as shown in Fig. 3, during 11 the filling of the bottle and until the bottle

neck is forced within the throat way. To accommodate the dogs 25 the casing 15 is provided with recesses 26 at its lower edge and registering openings 27 are formed in the lower edges of the casing and the throat piece through which the nose portions of the dogs project inwardly at a sufficient distance below the shoulder formed by the beginning of the tapering throat way to receive the crimped edges of the crown cap 18 between them. The nose portion of each of the dogs 25 is somewhat narrower than the remaining flat plate-like portion thereof, and the lower end of the nose is rounded to cause the dog to yield as the crown cap is inserted, while the upper edge of the nose is angular to engage the crown cap and prevent it from falling after it is inserted. The dogs are permitted to yield under spring pressure, the springs therefor being preferably leaf springs 28 which may be let into slots 29 cut in the lower edge of the casing from one recess 26 to another, as shown in Figs. 3 and 4, or which may be contained within grooves 30 cut in the outer surface of the casing near its lower end, as shown in Figs. 8 and 9. In either case each spring is designed to bear at its opposite ends upon two of the dogs near the lower ends thereof and to normally hold said dogs in their inner position but permit them to be forced outwardly by the insertion of the crown cap as described. With the springs 28 held in the slots 29 in the end of the casing, as shown in Figs. 3 and 4, the flange of the sleeve 19 will serve to hold them in place without further attachment, but with the springs contained within the grooves 30, as shown in Figs. 8 and 9, it is preferred to hold them in place at their middle portion by means of screws 31. At the opposite sides of the throat which are not occupied by the springs 28 there are formed the usual fill opening 32 and snift opening 33, which openings pass through the sleeve 19 and the throat piece 17 as well as through the casing.

In operation, the throat of the present invention performs the usual functions of throats for bottling machines and without the liability of the dogs becoming accidentally withdrawn. A further advantage for the throat of this invention is that by reason of the composition metal throat piece being formed of an unbroken ring, it is cheaper to manufacture and is quickly and easily repaired when the tapering throat way has become worn, it being only necessary then to remove the sleeve 19 and the dogs 25 and drive the throat piece out of the casing by means of the repair tool shown in Fig. 7. A new throat piece may then be inserted and is guided into its proper position to cause the several openings thereof to register with corresponding openings in the casing by fitting it to the key pins 23.

This substitution of a new throat piece for a worn one may be accomplished at the bottling establishment instead of having to send the throat to the factory, and as the throat pieces may be sold separate for this purpose the renewal may be made at a low cost and without loss of time. 70

While various forms of the invention have been shown and described for the purpose of clearly disclosing the same, it is 75 obvious that the invention is not limited to any specific form or arrangement of parts, except in so far as such limitations are specified in the claims.

What I claim as new and desire to secure 80 by Letters Patent is—

1. As a new article of manufacture, a throat piece adapted to be removably secured within the head of a capping machine comprising a tubular cylindrical casing provided with an integral inwardly extending flange at the upper end thereof, an annular throat piece provided with a tapered bore fitting within the interior of said casing and abutting the inwardly extending flange 85 thereof, said inwardly extending flange completely overlying the upper portion of the throat piece and being provided with an opening extending therethrough affording access to the top of the throat piece, 90 and means removably secured upon the lower end of the casing and underlying the lower end of said throat piece for holding the same within the said casing. 95

2. A throat for bottling machines, comprising a tubular casing, an inwardly extending flange thereon, a removable lining fitting within the casing and seated against the flange and comprising a throat piece with a tapering bore through its main portion and a bore of larger diameter therebeneath, a flanged sleeve fitting on the casing and engaging the lower end of the throat piece to hold it in place, there being recesses in the lower edge of the casing 100 with openings leading therefrom through the lower edge of the throat piece, spring pressed dogs contained within the recesses of the casing and projecting through said openings to engage a crown cap between them and the shoulder formed between the tapering bore and the bore of larger diameter of the throat piece, the flange of the sleeve serving to prevent the removal of the dogs from the recesses. 110

3. A throat for bottling machines, comprising a tubular casing, an inwardly extending flange thereon, a removable lining fitting within the casing and seated against the flange and comprising a throat piece 115 with a tapering bore through its main portion and a bore of larger diameter therebeneath, a flanged sleeve fitting on the casing and engaging the lower end of the throat piece to hold it in place, there being 120

recesses in the casing with openings leading therefrom through the throat piece, dogs contained within the recesses of the casing and projecting through said openings to engage a crown cap between them and the shoulder formed between the tapering bore and the bore of larger diameter of the throat piece, and springs mounted in the lower end of the casing each bearing 10 at its opposite ends against two of the dogs to hold them with pressure in their inner positions and permit them to recede to allow the crown cap to pass thereby.

4. A throat for bottling machines, comprising a tubular casing, an inwardly extending flange thereon, a removable lining fitting within the casing and seated against the flange and comprising a throat piece with a tapering bore through its main portion and a bore of larger diameter therebelow, a flanged sleeve fitting on the casing and engaging the lower end of the throat piece to hold it in place, there being recesses in the casing with openings leading 20 through the throat piece, dogs contained within the recesses of the casing and projecting through said openings to engage a crown cap between them and the shoulder formed between the tapering bore and the bore of larger diameter of the throat piece, there being grooves formed in the outer surface of the casing near its lower end from one recess to another, and springs contained within the grooves and secured at their middle portions to the casing and bearing at their opposite ends against two of the dogs to hold said dogs in their inner 25 position.

5. A throat for bottling machines, comprising a tubular casing, an inwardly extending flange thereon, a removable lining fitting within the casing and seated against the flange and comprising a throat piece with a tapering bore through its main portion and a bore of larger diameter therebelow, a flanged sleeve fitting on the casing and engaging the lower end of the throat piece to hold it in place, there being recesses in the casing with openings leading 30 through the throat piece, dogs contained within the recesses of the casing and projecting through said openings to engage a crown cap between them and the shoulder formed between the tapering bore and the bore of larger diameter of the throat piece, and springs fitted in the slits and bearing at the opposite ends against two of

the dogs to hold said dogs normally in their 35 inner position.

5. A throat for bottling machines, comprising a tubular casing, an inwardly extending flange thereon, a removable lining fitting within the casing and seated against 40 the flange and comprising a throat piece with a tapering bore through its main portion and a bore of larger diameter therebelow, a flanged sleeve fitting on the casing and engaging the lower end of the throat 45 piece to hold it in place, there being recesses in the casing with openings leading therefrom through the throat piece, dogs contained within the recesses of the casing and projecting through said openings to engage 50 a crown cap between them and the shoulder formed between the tapering bore and the bore of larger diameter of the throat piece, there being grooves formed in the outer surface of the casing near its lower 55 end from one recess to another, and springs contained within the grooves and secured at their middle portions to the casing and bearing at their opposite ends against two of the dogs to hold said dogs in their inner 60 position.

In testimony whereof, I affix my signature, in presence of two witnesses.
